Primary Examiner — Paula Greene(74) *Attorney, Agent, or Firm* — Laurence A. Greenberg; Werner H. Stemer; Ralph E. Locher(57) **CLAIM**

The ornamental design for binoculars, as shown and described.

DESCRIPTION

FIG. 1 is a top-plan view of the binoculars, showing my new design;

FIG. 2 is a left side-elevational view thereof;

FIG. 3 is a right side-elevational view thereof;

FIG. 4 is a bottom-plan view thereof;

FIG. 5 is a front-elevational view thereof;

FIG. 6 is a rear-elevational view thereof;

FIG. 7 is a perspective view thereof; and,

FIG. 8 is an enlarged view of the snap connector and ring thereof.

The broken lines in the figures form no part of the claimed design.
